UNITED STATES PATENT OFFICE.

HIRAM D. CURRIER, OF CHICAGO, ILLINOIS, ASSIGNOR TO KELLOGG SWITCHBOARD AND SUPPLY COMPANY, OF CHICAGO, ILLINOIS, A CORPORATION OF ILLINOIS.

INTERRUPTER FOR RINGING-CIRCUITS.

1,201,702.

Specification of Letters Patent. Patented Oct. 17, 1916.

Application filed November 19, 1914. Serial No. 872,908.

To all whom it may concern:

Be it known that I, HIRAM D. CURRIER, a citizen of the United States of America, residing in Chicago, county of Cook, and 5 State of Illinois, have invented certain new and useful Improvements in Interrupters for Ringing-Circuits, of which the following is a specification.

My invention relates to interrupters for 10 ringing circuits such as are used in connection with telephone systems. In telephone systems wherein so-called automatic or machine ringing is employed, ringing current usually is applied intermittently to the 15 called line and for this purpose interrupter devices of various kinds are used for interrupting the ringing relays in order to secure intermittent ringing periods. In connection with such systems it is desirable that 20 the exchange be divided into sections so that the ringing current is taken from the ringing generator at different periods in order to more equally distribute the load. Therefore the interrupter devices are usually 25 arranged so as to provide a number of different interrupter circuits. The most common means employed for this purpose is a motor driven interrupter device and it has been found comparatively expensive 30 especially in the smaller exchanges.

One of the principal objects of the present invention is to provide a simple, compact and comparatively inexpensive interrupter device and to this end I preferably employ 35 a number of relays coöperating in such a manner as to provide one or more interrupter circuits.

In the preferred form of my invention I employ eleven relays, this combination giving 40 four interrupter leads operating at different times. That is the four interrupter leads are closed and opened successively at different periods. Of course it is to be understood that the preferred form shown 45 is more for the purpose of illustration, as it will readily be seen after becoming familiar with the invention that other arrangements will readily occur to those skilled in the art.

My invention is adapted for other uses, 50 but for the purpose of illustration, I have shown the interrupter of my invention operating in connection with a cord circuit equipped with automatic ringing.

Referring now in general to the interrupter 55 circuits A in which the apparatus is in its unactuated position, it comprises pref-

erably eleven relays *a* to *k* inclusive, the relays *a* to *i* being slow acting relays and the relays *j* and *k* quick acting. Relays *a* to *i* are preferably adjusted alike, and so as to release their armature in about a half of a second after interruption of their circuits. This gives about one second ringing and four seconds silence.

To further illustrate my invention I have shown a cord circuit D for interconnecting two substations B and C which terminate in line circuits L and L¹ respectively, comprising line relays LR, cut-off relays CO, line signals S and multiple jacks J. The 70 cord circuit D is designed for automatic ringing and I have shown the interrupter circuit A in operative relation therewith. The cord circuit D comprises the usual answering and calling plugs P and P¹, answering and calling supervisory relays AS and CS, and supervisory lamps SS and SS¹. The automatic ringing apparatus of the cord circuit D comprises a party line ringing key RK, four ringing generators G, G¹, G² and 80 G³, a ringing control relay RCR, an interrupter relay IR, and a switching relay SW.

For the purpose of describing my invention, it will be assumed that the interrupter circuit A is associated with a 12 position 85 switchboard equipped with cord circuits as D. The interrupter A has four interrupter leads 1, 2, 3, 4, controlled by the operation of different connecting relays in the interrupter circuit and are multiply connected to 90 different positions of the switchboard preferably as follows: The lead 1 is common to the cord circuits D of the first, fifth and ninth positions, lead 2 to the second, sixth and tenth positions, lead 3 to the third, seventh and eleventh positions, and lead 4 to the fourth, eighth and twelfth positions.

The interrupter circuit A is constantly operating but may be shut off by switch 50 in the battery lead. I will now describe one 100 complete cycle of operation of the interrupter, and assuming that the apparatus is in condition as illustrated, a circuit for the relay *a* is first established traced from battery, the conductor 5 through *a*, conductor 6, normal contact 7 of the relay *i* to ground. The energization of the relay *a* closes a circuit for the connecting relay *b* from battery, conductor 5 through the relay *b*, alternate contact 8 conductor 9 to ground, whereupon its alternate contact 10 is closed, connecting battery to the interrupter lead 1.

The energization of relay *b* also closes a circuit for relay *c* from battery, conductor 5, through relay *c*, alternate contact 11 conductor 9 to ground whereupon a circuit is closed for the relay *d* from battery, conductor 5, through relay *d*, alternate contact 12 conductor 9 to ground. The relay *d* energizing closes circuit for relay *e* from battery, conductor 5, through relay *e*, alternate contact 13, conductor 9 to ground. The relay *e* is thus energized and closes circuit for the relay *f* from battery, conductor 5, relay *f*, alternate contact 14, conductor 9 to ground, and relay *f* in turn closes a circuit through connecting relay *g* from battery, conductor 5, through relay *g*, alternate contact 15, conductor 9 to ground. Relay *g* therefore closes a circuit for relay *h* from battery, conductor 5, through relay *h*, alternate contact 16, conductor 9 to ground, and a circuit for the relay *i* is thus closed from battery, conductor 5 through relay *i*, alternate contact 17, conductor 9 to ground. Thus all of the relays *a* to *i* are energized, having come up successively but of course in a fraction of a second. Upon the energization of the relay *i*, the energizing circuit for relay *a* is opened at normal contact 7 of relay *i* causing deenergization of relay *a* after a short period. Relay *a* deenergizing opens the circuit for relay *b* at its alternate contact 8 and the relay *b* deenergizing opens its alternate contact 10 which opens the interrupter lead 1 and closes its normal contact 10 which establishes an energizing circuit for connecting relay *j* from battery conductor 5, normal contact 10, through relay *j*, conductor 18, alternate contact 19 (still closed) conductor 9 to ground. Relay *j* now energizes and closes its alternate contact 20 placing the interrupter lead 2 in operative relation with its associated cord circuits in the second, sixth and tenth positions. Relay *b* having deenergized opens the circuit for relay *c* which in turn opens the circuit for relay *d* and relay *d* opens the circuit for relay *e* which relay *e* deenergizing opens its alternate contact 19 to restore the relay *j* and open the interrupter lead 2. The deenergization of relay *e* again closes its normal contact 19 which establishes an energizing circuit for connecting relay *h* from battery, conductor 5, alternate contact 21, conductor 22, through relay *h* and normal contact 19 to ground. Relay *h* energizing closes its alternate contact 23 which places the lead 3 in operative relation with its associated cord circuits. The relay *e* deenergizing opens the circuit for the relay *f* which in turn opens the circuit of connecting relay *g* and the relay *g* deenergizing opens its alternate contact 21 which interrupts the circuit of the relay *h* which now disconnects lead 3 from its associated cord circuits. Relay *g* deenergizing again closes

its normal contact 21 placing the interrupter lead 4 in operative relation with its associated cord circuits and opens the circuit for relay *h* upon deenergization of which the circuit for relay *i* is interrupted. Relay *i* deenergizing closes its normal contact 7 which again completes a circuit for the relay *a* followed by the successive operations of the other relays as before. I have found by experiment that by timing the relays so that one cycle of operation occurs in five seconds, very satisfactory results are attained as this places each interrupter lead in operative relation with its associated cord circuits for one second of time, and disassociates each one for a period of four seconds.

I will now describe the interrupter circuit A operating in connection with the cord circuit D, which we will assume is one of the fifteen cord circuits of the first position with which the interrupter lead 1 is common. Assuming a subscriber at substation A wishes to converse with a subscriber at substation C, the removal of the receiver at substation B closes an energizing circuit for the line relay LR to light line signal S. The operator now inserts the plug P into the jack J, operating the cut-off relay CO from battery through the impedance coil R, the contacts of the plug P and jack J through CO to ground, which interrupts the energizing circuit of the line relay LR to efface the line signal S. The answering supervisory relay AS is also operated from battery through the coil P, through the substation, the winding of relay AS to ground, opening its normal contact to prevent the premature lighting of supervisory signal SS.

Assuming that substation C is wanted and its line is idle the operator inserts the plug P^1 into the jack J^1 closing an energizing circuit for the cut-off relay CO^1 and switching relay SW in series from battery through the winding of relay SW, sleeve contacts of the plug P^1 and jack J^1 , the winding of relay CO^1 to ground. The relay SW closes its alternate contact 24, closing a circuit for the supervisory signal SS^1 which remains lighted until the called for subscriber answers. The operator now fully depresses the proper ringing plunger, p , p^1 , p^2 or p^3 of the party line ringing key RK, and assuming that it is the plunger p which is depressed, the end springs 26, 27 momentarily assume their alternate positions, the spring 27 closing an energizing circuit for the ringing control relay RCR, traced from battery, through the winding of relay RCR, conductor 28, alternate contact 27, conductor 29, normal contact 25 and alternate contact 24 to ground. Although the circuit of relay RCR is interrupted at contact 27 when the operator removes pressure from the actuated plunger, the relay RCR closes a locking cir-

cuit for itself traced from battery, the alternate contact 30 of the relay RCR, normal contact 25 of relay CS, alternate contact 24 of relay SW to ground. Upon the energization of the relay RCR, its alternate contact 31 is closed, which connects interrupter lead 1 of the interrupter circuit A with the interrupter relay IR of the cord circuit D. Assuming that the relay *b* of the 10 interrupter circuit A is in its energized condition as before described and its alternate contact 10 closed, an energizing circuit for the relay IR is established traced from battery, conductor 5, alternate contact 10 of relay *b*, interrupter lead 1, alternate contact 31, normal contact 26, through the winding of relay IR to ground. Upon energization of relay IR it closes its alternate contact 32 which connects ringing current to the called 15 line from the ungrounded pole of the generator G, alternate contact *p*, the alternate contact 32, the alternate contact 33, tip contacts of the plug P¹ and jack J¹, through the condenser and call bell of the called 20 substation C, the sleeve contacts of the jack J¹ and plug P¹, the alternate contact 34 of the relay IR to battery and ground. The relay IR is energized each time the interrupter lead 1 is connected to battery through contacts of relay *b*. As before described the 25 interrupter relay IR is energized each time the relay *b* of the interrupter circuit A is energized, thus connecting ringing current to the wanted line for about one second of 30 the time and allowing a silent interval of about four seconds which are the intervals that the relay *b* remains energized and de-energized.

When the called subscriber answers an 40 energizing circuit for the relay CS is established over the line and opens its normal contact 25 which interrupts the locking circuit for relay RCR, which de-energizes and opens the circuit of relay IR at its alternate 45 contact 31. The opening of alternate contact 31 disconnects the lead 1 which prevents the relay IR from again operating. The opening of contact 25 of relay CS effaces the signal SS¹. When conversation has been 50 completed and the receivers have been replaced on their respective switch-hooks, the relays AS and CS re-energize to again light the supervisory signals SS and SS¹ whereupon the operator withdraws plugs P and P¹ from the jacks J and J¹ restoring the 55 cord and link circuits.

From the foregoing it will be seen how the four connecting relays *b*, *j*, *k* and *g* successively energize the interrupter leads, 1, 2, 60 3 and 4 respectively, the slow action of the relays *a* to *i* inclusive giving ringing and silent periods of sufficient duration. It will be evident that by increasing or diminishing the speed of these relays *a* to *i* the ringing and silent periods may be varied. It

will also be apparent that the number of relays may be increased or diminished so that various numbers of ringing leads can be provided. I also contemplate using my invention in various other ways than that shown and therefore I do not desire to be limited to the exact structure as shown and described but aim to cover all that which comes within the spirit and scope of the appended claims.

Having described my invention, what I claim as new and desire to secure by United States Letters Patent is:

1. An interrupter system of the character described comprising a series of relays, a source of current, circuit connections between said relays for effecting an automatic continuous sequential energization and de-energization thereof, the last relay of the series operating to de-energize the relays of the series each time that it is energized, and a plurality of interrupter leads connected to different ones of said relays whereby successive energizations of said leads are effected.

2. An interrupter system of the character described comprising a series of relays, a source of current, circuit connections between said relays for effecting an automatic continuous sequential energization and de-energization thereof, one relay of the series controlling a substantially simultaneous energization of the relays of the series, and interrupter leads extending from contacts of different ones of said relays whereby said leads are intermittently energized at different periods for the different leads.

3. An interrupter system of the character described comprising a series of relays, a source of current, interrupter leads extending from contacts of certain ones of said relays, and circuit connections between said relays whereby the first relay of the series controls the successive energization of the relays in the series and the last relay in the series controls the successive de-energization of the relays in the series for effecting energizations and de-energizations of short and long periods respectively of said interrupter leads.

4. An interrupter system of the character described comprising a series of electromagnets, contacts controlled thereby, a source of current, circuit connections between said electromagnets and contacts whereby when the first electromagnet of the series is energized the other electromagnets are successively energized and whereby when the last electromagnet of the series is energized the electromagnets of the series are de-energized, and interrupter leads connected to certain of said contacts whereby said leads are intermittently closed at different periods for the different leads.

5. An interrupter system of the character

described comprising a series of relays, a source of current, circuit connections whereby when the first relay of the series is energized, it operates to energize the series of 5 relays and whereby when the last relay of the series is energized, it operates to deenergize the series of relays, and interrupter leads extending from contacts of different ones of said relays whereby said source of 10 current is successively connected to and then successively disconnected from said leads.

6. An interrupter system of the character described comprising a plurality of relays 15 certain of which are connecting relays, interrupter leads extending from contacts of the connecting relays, a source of current, and circuit connections extending between certain of the contacts of said relays and 20 the electromagnets of the relays whereby an automatic continuous energization and deenergization of said relays is effected to successively operate the ringing lead contacts intermittently, one relay of said plurality of 25 relays controlling the energization of a series of said relays and another of said relays controlling the deenergization of the said series of relays.

7. An interrupter system of the character described comprising a series of relays, a source of operating current, circuit connections between said relays whereby the first relay of the series causes the consecutive energization of said series of relays and 30 whereby the last relay of the series causes the consecutive deenergization of the relays of the series, and interrupter leads connected to contacts of certain of said relays whereby said leads are intermittently closed at different 35 periods for the different leads.

8. An interrupter system of the character described comprising a series of relays, a source of operating current, circuit connections between said relays whereby one relay of the series causes the consecutive energization of said series of relays and whereby another relay of the series causes the consecutive deenergization of the relays of the series, and interrupter leads connected to 45 contacts of certain of said relays whereby said leads are intermittently closed at different periods for the different leads.

9. An interrupter system of the character described comprising a series of relays, a source of current, circuit connections between said relays whereby when the first relay of the series energizes the remaining relays are energized consecutively and whereby when the last relay of the series energizes the first relay of the series deenergizes and operates to deenergize the other relays consecutively, and a plurality of interrupter leads connected to different ones of 55 60

said relays whereby successive energizations of said leads are effected.

10. An interrupter system of the character described comprising a series of relays, circuit connections extending between said relays for effecting an automatic continuous consecutive energization and deenergization 70 thereof, the first and last relays of the series controlling the energization and deenergization of the relays of the series, a source of current, and interrupter leads extending from contacts of certain of said relays whereby said source of current is intermittently connected to said interrupter leads.

11. An interrupter system of the character described comprising a series of relays, 80 a source of current, interrupter leads, and connections between said relays for effecting an automatic continuous energization and deenergization thereof effective to connect said source of current to said leads at 85 different periods, the first relay of the series controlling the energization of the relays of the series and the last relay of the series controlling the deenergization of the relays of the series.

12. An interrupter system of the character described comprising a series of relays, a source of current, circuit connections between the relays whereby when the first relay of the series energizes all of said relays of the 95 series are energized in rotation and whereby when the last relay of the series energizes the first relay of the series deenergizes and operates to deenergize in rotation all of the relays in the series, and interrupter leads 100 extending from contacts of different ones of said relays, said relays operating to connect said source of current intermittently to said interrupter leads at different periods for the different leads.

13. An interrupter system of the class described comprising a series of slow acting relays, a source of current, interrupter leads, circuit connections between said relays whereby the energization of one of said relays causes substantially the simultaneous energization of the other relays of the series and the energization of another one of said relays causes the relays of the series to deenergize slowly and consecutively, said operation of said relays operating to differentially connect said source of current to said interrupter leads.

Signed by me at Chicago, county of Cook and State of Illinois, in the presence of two 120 witnesses.
